(57) **CLAIM**

The ornamental design for a VR face cover, as shown and described.

DESCRIPTION

FIG. 1 is a perspective view of a VR face cover showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear side perspective view thereof; and,

FIG. 9 is an enlarged detail view of area 9 shown in FIG. 1. Any shading and cross-hatching are not features of the design but are utilized to illustrate the surface contours of the VR face cover design in the drawings.
